UNITED STATES PATENT OFFICE.

HENRY ALBERT STEBER, OF UTICA, NEW YORK.

MACHINE FOR MAKING MATCH-SPLINTS.

SPECIFICATION forming part of Letters Patent No. 290,492, dated December 18, 1883.

Application filed July 6, 1883. (Model.)

To all whom it may concern:

Be it known that I, HENRY A. STEBER, of Utica, in the county of Oneida and State of New York, have invented a new and Improved 5 Method of and Machine for Making Matches, of which the following is a full, clear, and exact description.

This invention has reference to improvements in machines for making match-splints; 10 and it consists in the detailed construction of the die and of the combination and arrangement of parts, substantially as hereinafter fully set forth and claimed.

Reference is to be had to the accompanying 15 drawings, forming part of this specification, in which similar letters of reference indicate corresponding parts in all the figures.

Figure 1 is a side elevation of my improved match-making machine. Fig. 2 is a sectional 20 elevation of Fig. 1 on the line xx . Fig. 3 is a plan view of the die. Fig. 4 is a sectional elevation of said die; and Fig. 5 is an enlarged partly sectional and partly perspective view of the die, parts thereof being broken away.

25 I make a die, a , consisting of a steel plate with any approved number of holes, b , bored or otherwise formed through it from side to side, of suitable size to form match-sticks l from blocks of wood forced through the holes, 30 and the holes being as close together as will allow sufficient thickness of the partitions c for cutters to split the block into suitable sticks for matches, the upper edges of these partitions being sharpened suitably for the 35 purpose. The holes may be square, round, or any other approved shape, but probably round will be the most preferable form, as they can be formed in that shape by boring with a drill better than they can be made in other 40 forms, and the round form is the best for the match-sticks. The rows of holes are arranged parallel to planes traversing the die at right angles to each other, thereby imparting square upper edges (or nearly so) to the said holes,

45 whose separating-partitions, as already stated, are sharpened to effect the cutting of the entire block of wood into whole splints, which avoids the producing of any half-splints, as experienced in the honey-combed arrangement 50 of the holes. Further, I arrange the cutting-edges of the holes some distance below the face

of the die by forming in the die above and around the holes a depression or concavity, b' , as seen in Figs. 3 and 4, whereby the force of the block of wood will not be received directly upon the face of the die, but upon the cutting-edges of the holes and below the face, which obviates the shock or concussion that would result by the forcible contact of the block of wood with the face of the die. The 60 sinking of the upper edges of the holes below the face of the die and arranging the same in rows parallel to planes traversing the die-block at right angles to each other, and then sharpening the partitions, leaves a post, d , at 65 a point central to every four of the series of holes, with sharpened corner edges and a reduced or tapering upper end or point, whereby the descending block of wood will be caused to have a minimum surface of contact with 70 the die, since the pointed sharpened posts first puncture and begin the cutting of the block to open the way for the entrance of the sharpened partitions of the die-holes, more effectually preventing the shock or concussion. This die 75 75 I arrange in a notch or recess, d , in a suitable stock, e , over which there is an opening at k through the side of the stock large enough to insert the blocks to be formed into match-sticks, to set them up endwise on the die a 80 and along the three sides of the chamber into which the blocks are placed, and above said chamber a plunger, f , is arranged to slide in way j , for being pressed down on the blocks to force them through the die. In this case I 85 have provided the said plunger with a small rod, g , for each hole of the die, to descend into the holes and force the sticks entirely through the die-plate and discharge them; but they may be omitted and the plain flat head of the 90 plunger used, in which case the sticks will remain in the dies until forced out by the next block. Any approved means of applying power to the plunger for working it may be 95 employed.

For receiving the bunches of sticks from the die and carrying them therefrom to the dipping and priming apparatus, I propose to employ an endless chain of links, h , having a suitable opening to receive the sticks from the die 100 and hold them with sufficient friction to carry them until forced out by some suitable device,

which chain I propose to arrange to run under the die-stock *e*, and gear it so that a link will be ready for its bunch of sticks at every operation of the plunger.

5 The chain-links may have any approved contrivance of connecting-joints at *i* for pivoting them together, and any approved means of working them, provided the same be connected with the plunger-gear to operate synchronously therewith.

10 The blocks may be grooved or not on one end to form the points to be dipped and primed before being forced through the die; but it will be preferred to groove them first, because 15 it can be done cheaper and better than the sticks can be pointed afterward.

I do not abandon or dedicate to the public any patentable feature set forth herein and not hereinafter claimed, but reserve the right 20 to claim the same either in a reissue of any patent that may be granted upon this application or in other applications for Letters Patent that I may make.

Having thus described my invention, I claim 25 as new and desire to secure by Letters Patent—

1. In a match-splint-making machine, the combination, with the stock *e*, having the socket

or recess, *d*, of the die *a*, having the crossing partitions *c*, between which are series of apertures *b*, said partitions having sharpened edges, the chain of links *h*, and the plunger *f*, having a series of small rods, *g*, adapted to enter the apertures *b* of the die *a*, substantially as and for the purpose set forth. 30

2. In a match-splint-making machine, the die plate or block having rows of holes arranged parallel to planes traversing the said plate or block at right angles to each other, with the upper edges of their separating partitions sharpened and arranged below the die-face, and a sharpened pointed post at a point central to every four of the series of die-holes, substantially as and for the purpose set forth. 35

3. The die consisting of the plate having sunken rows of holes, said rows being arranged parallel to planes traversing the die at right angles to each other, the upper edges of the separating-partitions of said holes being sharpened, substantially as shown and described, and for the purpose set forth. 40 45 50

HENRY ALBERT STEBER.
